BRACKET FOR A FLASHLIGHT OR THE LIKE

Ray D. Arbogast, Freeport, Ill., assignor to Burgess Battery Company, Freeport, Ill., a corporation of Delaware

Application February 14, 1956, Serial No. 40,160

Term of patent 14 years

(Cl. D48—24)

Fig. 1 is a perspective view of a bracket for a flashlight or the like embodying my new design;

Fig. 2 is a rear view of the bracket shown in Fig. 1;

Fig. 3 is a left side view thereof; and

Fig. 4 is a top view thereof.

I claim:

The ornamental design for a bracket for a flashlight or the like, as shown.
